[57] ABSTRACT

Process for production of fertilizers from phosphoric and sulfuric acids, anhydrous ammonia, and urea, and for the production of high-analysis granular ammonium phosphates, ammonium phosphate sulfates, and urea-ammonium phosphate sulfates—some with polyphosphate contents of up to 68 percent of the total P₂O₅. A specially designed pipe-cross reactor is used to produce a homogeneous melt or slurry of low moisture content

from the reactants and thus eliminates the need for a preneutralizer as used in many prior-art granular fertilizer processes. Because of the low melt or slurry moisture content, the dryer is eliminated. The elimination of these two items greatly simplifies pollution abatement, since both items are sources of fumes and dust. The equipment used to produce granular monoammonium phosphate, diammonium phosphate, urea-ammonium phosphate sulfate, and ammonium phosphate sulfate fertilizers is inexpensive and simple to operate. The products produced are dust-free and of such particle size that they are well suited for bulk blends. Ammonium phosphate sulfate grades of 12-48-0, 6-24-24, 13-13-13, 10-40-10, a monoammonium phosphate grade of 11-55-0, a diammonium phosphate and diammonium phosphate sulfate grade of 18-46-0, and urea-ammonium phosphate sulfate grades of 33-11-0, 17-17-17, and 20-10-10 have been produced.
